UNITED STATES PATENT OFFICE.

HARRY FRIEDMANN, OF BALTIMORE, MARYLAND, ASSIGNOR, BY MESNE ASSIGNMENTS, TO CLUETT, PEABODY & CO., INC., OF TROY, NEW YORK, A CORPORATION OF NEW YORK.

FOLD-CUFF.

1,079,484.

Specification of Letters Patent. Patented Nov. 25, 1913.

Application filed July 27, 1912. Serial No. 711,809.

To all whom it may concern:

Be it known that I, HARRY FRIEDMANN, a citizen of the United States, residing at Baltimore, State of Maryland, have invented certain new and useful Improvements in Fold-Cuffs, of which the following is a specification.

The invention relates to such improvements and consists of the novel construction 10 and combination of parts, hereinafter described and subsequently claimed.

Reference may be had to the accompanying drawings, and the reference characters marked thereon, which form a part of this 15 specification. Similar characters refer to similar parts in the several figures therein.

Figure 1 of the drawings is a view in perspective of a broken-away end of a shirt-sleeve having a reversible fold cuff embodying my invention, the cuff being folded outward. Fig. 2 is a similar view with the cuff folded inward. Fig. 3 is a partial section taken through the cuff longitudinally of the sleeve.

25 My invention relates to shirts having folded cuffs, commonly called French cuffs, the cuff being folded over upon itself along its longitudinal middle line so as to expose to view its folded edge at the end of the 30 sleeve and the end edges of four thicknesses of cuff along the side of the sleeve near its end.

As heretofore constructed, such a folded cuff was adapted for use only when folded 35 over outwardly upon itself, because the outer plies of the cuff, when attached to the sleeve, were stitched down close to its edge upon the sleeve so as to present a noticeably different appearance from the exposed edge 40 of the outwardly folded-over portion of the cuff in use, so that if the folded portion of the cuff were folded inwardly instead of outwardly, the reversal of the cuff would be quite apparent.

45 The principal object of my invention is to adapt a fold or French cuff for use either in its ordinary form or in reversed form without rendering the reversal apparent to a casual observer. This I am able to accomplish by providing the cuff with outer 50 plies presenting a folded edge along the sleeve-end of the cuff and free from the sleeve for a substantial distance from said folded edge whereby the folded edge of said

plies presents substantially the same appearance as does the outwardly folded-over edge of the cuff. 55

Referring to the drawings wherein the invention is shown in its preferred form, 1 presents the shirt-sleeve, 2 the attached portion of the cuff, and 3 the fold-over portion of the cuff. Along its attached end, the attached portion, 2, of the cuff has outer plies, 4, which present a folded edge, 5, and are attached to the sleeve by a line of stitching, 6, at a substantial distance from the folded edge, 5, forming a free flap along the attached edge of the cuff as shown in Figs. 2 and 3.

As shown in Fig. 3, the inner ply, 7, of 70 the cuff is first attached to the sleeve by a seam, 8, and the outer plies, 4, are attached to the sleeve as well as to the inner ply, 7, by a line of stitching, 6, at a substantial 75 distance from the folded edge, 5, of said outer plies leaving the folded portions of said outer plies free from the sleeve from their folded edges, 5, to said line of stitching, 6.

One of the outer plies, 4, may be omitted 80 if desired.

The cuff is provided with four button-holes, two located in the attached portion of the cuff and two in the fold-over portion, all four button-holes being adapted to register, when the cuff is folded either inwardly or outwardly, to receive a cuff-button or link, 12, by means of which all four thicknesses of the folded cuff are held together. The button-holes 13 in the fold-over portion 90 of the cuff are located somewhat farther from the edge thereof than the button-holes 9 in the attached portion are from the edge, 5, so that when the cuff is folded outwardly, the folded-over portion will cover and practically conceal from view the folded edge, 5. 95 The buttonholes, 9 and 13, are diagrammatically shown in Fig. 3, and the folded line of the cuff is indicated by the broken line, 14, in said figure, from which it will be seen that when folded upon the line, 14, the buttonhole, 13, will register with the buttonhole, 9, and the folded-over portion of the cuff will extend somewhat above the free edge 5. 100

As thus constructed, the edge of which ever portion of the cuff which is outwardly exposed presents in appearance, adjacent to the sleeve, substantially the same free folded 105

edge, said free edge, when the cuff is outwardly folded, being formed by the outer end of the cuff; and said free edge, when the cuff is inwardly folded, being formed by the free flap portion of the outer plies terminating in the folded edge, 5. To the casual observer, the appearance is the same in either case, so that when the cuff is reversed, the attention of the observer is not directed to this fact. The cuff can thus be worn outwardly folded until soiled and then reversed and inwardly folded to expose to view unsoiled surfaces, thus adding to the utility of the garment.

15 What I claim as new and desire to secure by Letters Patent is--

A sleeve having a reversible soft fold-cuff attached thereto, said cuff having an outer ply presenting a folded edge adjacent to the sleeve and attached to the sleeve at a substantial distance from said folded-edge,

whereby a free flap is formed along the outer side of the cuff adjacent to said sleeve, the attached portion of said cuff being provided with a pair of button-holes and the 25 folded-over portion of said cuff being provided with a pair of button-holes at a greater distance from its edge than are the button-holes in the attached portion from the folded-edge thereof, all of said button-holes 30 being adapted to register with each other and to receive a single cuff-button whereby said folded edge is covered by the edge of the fold-over portion when the cuff is folded outwardly.

In testimony whereof, I have hereunto set my hand this 19th day of July, 1912.

HARRY FRIEDMANN.
